STRANDING MACHINE

Dana B. Carleton, Trenton, N. J., assignor to United States Steel Corporation, a corporation of New Jersey

Application November 24, 1952, Serial No. 322,311

6 Claims. (Cl. 57—71)

This invention relates to improvements in stranding machines.

As used herein, the term "stranding machine" refers to a machine which twists either a plurality of component wires together to form a strand or a plurality of component strands together to form a rope or cable. The term "stranded wire structure" refers either to a plurality of component wires twisted together and constituting a strand or a plurality of component strands twisted together and constituting a rope or cable. The present invention is concerned with stranding machines of the type in which the supply reels rotate on stationary axes and the take-up reel is mounted in a frame rotatable longitudinally about the axis of the stranded wire structure.

An object of the invention is to provide an improved stranding machine which is of simpler construction and has fewer parts than previous machines with which I am familiar.

A further object is to provide a stranding machine of the foregoing type in which the haul-off mechanism, usually considered necessary, is eliminated altogether.

A further object is to provide a stranding machine which is equipped with means situated in advance of the closing die for controlling the rate of travel of the component wires or strands to furnish the desired lay.

A further object is to provide an improved stranding machine in which the take-up reel has the further function of pulling the stranded wire structure through the machine and in which the rate of travel of the component wires or strands is controlled by a lay control drum situated in advance of the closing die, thereby dispensing with the usual haul-off mechanism.

In accomplishing these and other objects of the invention, I have provided improved details of structure, a preferred form of which is shown in the accompanying drawing, in which:

Figure 1 is a top plan view of an improved stranding machine which embodies features of the present invention;

Figure 2 is a side elevational view of the machine; and

Figure 3 is a side elevational view on a larger scale of the guide plate and presetting pins.

The stranding machine of the present invention comprises a base 10 on which are mounted in succession a lay control drum 12, a spreader or guide plate 13, a closing die 14, a rotary straightener 15, and a take-up reel 16. The component wires or strands W are fed to the machine from the left from supply reels, not shown, and at least one component passes over tensioning means T shown diagrammatically in Figure 1. The machine has a drive motor 17 which is mounted on a motor base 18 situated beside the base 10. A longitudinally extending drive shaft 19 is rotatably mounted in bearings 20 on base 18 and is coupled to said motor for driving the various mechanisms, as hereinafter explained.

The lay control drum 12 is fixed to a transversely extending rotatable power driven shaft 21. The bearings

2

for shaft 21 are carried in bearing stands 22 fixed to the base 10 adjacent the left end thereof. The drum rotates in a clockwise direction and is of relatively large diameter and has one or more circumferential grooves 23. The drive means illustrated for rotating the shaft 21 includes a worm gear 24 fixed to this shaft, a worm 25 fixed to a longitudinally extending shaft 26, and a "Waterbury" drive for rotating the last named shaft. The "Waterbury" drive includes a motor 27 mounted on the base 10 and whose output shaft is coupled to shaft 26, a pump 28 mounted on the motor base 18 and whose input shaft is coupled to the end of the drive shaft 19, and pipes 29 and 30 which connect said motor and pump. The "Waterbury" drive is not described in detail, since per se such drives are well known, but reference can be made to Francis Patent No. 1,774,880, dated September 2, 1930, for a complete description of the principles involved.

To the right of the lay control drum 12, the base 10 carries uprights 31 and 32 which support the guide plate 13 and the closing die 14. The guide plate 13 is slidably mounted on a pair of longitudinal rods 33 which extend between the uprights 31 and 32. A longitudinal shaft 34 is rotatably mounted in a bearing on the upright 31 and has a screw-threaded portion which is engaged with the lower part of the guide plate 13. Preferably shaft 34 carries a hand wheel 35. Manual rotation of the hand wheel 35 and shaft 34 adjusts the longitudinal position of the guide plate 13. The rear face of the guide plate carries a cone 36 on which are mounted presetting pins 37. The closing die 14 is mounted on the upper end of the upright 32 to the right of the guide plate and is aligned therewith. The closing die is not shown in detail, since per se it can be of any standard or desired construction. Reference can be made to my joint patent with William H. Simcoe No. 2,556,164, dated June 12, 1951, for a complete showing of several suitable forms of closing die.

For driving the closing die 14 (and also the straightener 15 and take-up reel 16) a longitudinally extending countershaft 38 is rotatably mounted in bearings 39 carried by the base 10. Shaft 38 is driven from the drive shaft 19 by a chain and sprocket mechanism 40, and is drivingly connected with the closing die by another chain and sprocket mechanism 41.

To the right of the closing die 14 the base 10 carries a stand 42 on which the straightener 15 is mounted in aligned relation with said die. The straightener is not shown in detail, since per se it is not part of the present invention, but can be of any standard or desired construction. Reference can be made to Roberts Patent No. 2,007,345, dated July 9, 1935, for a complete showing of one suitable form of straightener. The straightener is driven from the countershaft 38 by a belt pulley mechanism 43.

To the right of the straightener 15 the base 10 carries a pair of longitudinally spaced bearing stands 44 and 45 on which are mounted a pair of aligned bearings 46 and 47 respectively. A rectangular cradle or frame 48 is mounted for rotation on a longitudinal axis in bearings 46 and 47, its axis of rotation being coaxial with that of the closing die 14 and the straightener 15. The frame is driven from the countershaft 38 by another chain and sprocket mechanism 49. The side members of the frame contain aligned bearings 50. The take-up reel 16 has journals 51 which are removably mounted in bearings 50 for rotation on an axis perpendicular to the axis of rotation of the frame.

A gear 52 is rotatably mounted in frame 48 coaxial with the bearings 50 and is keyed to one of the journals 51 of the take-up reel. The journal which supports the right end of the frame in the bearing 47 contains an axial bore within which a longitudinal shaft 53 is mounted for rotation relative to the frame. The inner end of

shaft 53 carries a bevel gear 54 which is connected with gear 52 via a gear train 55 such as that illustrated in Figure 1. In order to drive the take-up reel, it is only necessary to produce relative rotation between the shaft 53 and the frame 48, and any conventional means can be used for this purpose. I have illustrated a friction mechanism which includes a drum 56 on the shaft 53 and a plurality of brake bands 58 surrounding said drum. As the frame 48 rotates on its longitudinal axis, the friction mechanism retards rotation of the shaft 53 and thus produces relative rotation between the shaft and frame. This relative rotation is transmitted to the take-up reel 16 via the bevel gear 54, gear train 55 and gear 52. The rate of rotation of the take-up reel is controlled by adjusting the degree of tightness and thus the retarding effect of the brake bands 58. It is seen that no special drive means are required for rotating the take-up reel, but rotation thereof is effected merely by retarding the shaft 53.

In advance of the take-up reel 16 the frame 48 carries a level winding mechanism. This mechanism includes a double-threaded shaft 59 rotatably mounted in bearings on the side members of the frame, a driving connection 60 between said shaft and one of the journals 51 of the reel, and a traversing device 61 carried by said shaft. As reel 16 revolves, it rotates shaft 59 and moves the traversing device back and forth across the length of the reel.

In operation, all or some of the component wires or strands W, as they enter the machine, pass around grooves 23 in the circumference of the lay control drum 12. One or more convolutions of these components can be thus wrapped around the drum, which is of sufficient diameter not to induce any bending set in the components. The drum is driven at a definite rate in such a manner as to maintain back tension on the components so that they can be properly stranded in the closing die 14. The speed of rotation of the drum determines the length of lay in the finished stranded wire structure, and the drum maintains a substantially uniform position or point of lay. While all of the component wires or strands may, if desired, be wrapped around the drum, this may not always be necessary or desirable. It is a requirement of the invention, however, that at least one of the components be wrapped around the drum. For some stranded wire structures which have core members for tensile strength, it may be necessary to wrap only the core member. Components not wrapped around the drum can pass either to the side or over the top thereof as desired.

The component wires or strands next pass in succession over the presetting pins 37 on cone 36 and through the guide plate 13, the closing die 14 and straightener 15, all of which function in the usual manner. The longitudinal position of the guide plate 13 is of course adjusted to obtain the natural point of twist for the particular sizes, grades and number of components being stranded.

After leaving the straightener, the finished stranded wire structure passes directly to the traversing device 61 and thence to the take-up reel 16, there being no intervening haul-off mechanism. Rotation of the take-up reel supplies the necessary tension for pulling the structure through the machine, and to make this possible, the reel and its drive may be made somewhat heavier than usual. The drum 12, rather than the usual haul-off mechanism, controls the lay, as already explained. Thus the drum enables the haul-off mechanism to be eliminated.

In the event one or more component wires or strands breaks in the stranding operation, the machine readily can be reversed and the strand retracted to repair the broken components. The presence of haul-off mechanism has always complicated such reversals.

While I have shown and described only a single embodiment of the invention, it is apparent that modifica-

tions may arise. Therefore, I do not wish to be limited to the disclosure set forth but only by the scope of the appended claims.

I claim:

- 5 1. A stranding machine comprising a rotatable lay control drum adapted to have components of a stranded wire structure wrapped therearound, means following said drum for closing the components into a stranded wire structure, a frame rotatable on the axis of the stranded wire structure, a take-up reel rotatably mounted in said frame and adapted to tension the stranded wire structure and its components for pulling them through said closing means without intervening haul-off mechanism, and drive means for rotating said drum, said frame and said reel in a timed relation, with said drum holding back and tensioning components which are wrapped around it.
- 10 2. A stranding machine comprising a rotatable lay control drum adapted to have components of a stranded wire structure wrapped therearound, drive means for rotating said drum, guide means, a closing die and a straightener following said drum and adapted to act successively on the components after they leave said drum for forming them into a straightened stranded wire structure, a level winding mechanism and a take-up reel directly following said straightener without intervening haul-off mechanism, said take-up reel being adapted to tension the stranded wire structure and its components for pulling them through the machine, and drive means for rotating said reel, the two drive means operating in a timed relation so that said drum holds back and tensions components which are wrapped around it.
- 15 3. A stranding machine comprising a rotatable lay control drum adapted to have components of a stranded wire structure wrapped therearound, drive means for rotating said drum, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 20 4. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame mounted for rotation on the axis of the stranded wire structure directly following said straightener, a take-up reel and a level winding mechanism mounted in said frame and adapted to receive the stranded wire structure directly from the straightener without intervening haul-off mechanism, drive means for rotating said frame, and adjustable means for rotating said reel as said frame rotates, rotation of said reel being adapted to tension the stranded wire structure and its components for pulling them through the machine, the two drive means operating in a timed relation so that said drum holds back and tensions components which are wrapped around it.
- 25 5. A stranding machine comprising a rotatable lay control drum adapted to have components of a stranded wire structure wrapped therearound, drive means for rotating said drum at a predetermined rate, means following said drum for closing the components into a stranded wire structure, a frame rotatable on the axis of the stranded
- 30 6. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 35 7. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 40 8. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 45 9. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 50 10. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 55 11. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 60 12. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 65 13. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.
- 70 14. A stranding machine comprising a rotatable lay control drum adapted to have components of a stranded wire structure wrapped therearound, drive means for rotating said drum at a predetermined rate, means following said drum for closing the components into a stranded wire structure, a frame rotatable on the axis of the stranded
- 75 15. A stranding machine comprising a rotatable lay control drum having a circumferential groove adapted to receive components of a stranded wire structure wrapped therearound, drive means for rotating said drum at a predetermined rate, guide means, a closing die and a straightener following said drum and adapted to act successively on the components after they leave said drum for forming them into a straightened stranded wire structure, a frame rotatable on the axis of the stranded wire structure directly following said straightener, a take-up reel and a level winding mechanism mounted in said frame and adapted to receive the stranded wire structure directly from the straightener without intervening haul-off mechanism, said take-up reel being adapted to tension the stranded wire structure and its components for pulling them through the machine, and drive means for rotating said frame and said reel, the two drive means operating in a timed relation so that said drum holds back and tensions components which are wrapped around it.

wire structure, a take-up reel rotatably mounted in said frame, means for rotating said frame, a shaft coaxial with the axis of rotation of said frame and rotatable relative to said frame, gearing connecting said shaft and said reel for rotating the reel on relative rotation between the shaft and frame, drive means for rotating said frame, and friction means for retarding rotation of said shaft and thus rotating said reel, rotation of said reel being adapted to tension the stranded wire structure and its components for pulling them through said closing means without intervening haul-off mechanism, the two drive means operating in a timed relation so that said drum holds back and tensions components which are wrapped around it.

6. A stranding machine comprising a rotatable lay control drum adapted to have components of a stranded wire structure wrapped therearound, drive means for rotating said drum at a predetermined rate and thereby controlling the rate of advance of the components, means for closing the components into a stranded wire structure, a frame

10

5

rotatable on the axis of the stranded wire structure, a reel mounted for rotation in said frame and adapted to act both as a take-up reel for the stranded wire structure and as a means for tensioning the stranded wire structure and its components for pulling them through said closing means, and drive means for rotating said frame and said reel, the two drive means operating in a timed relation so that said drum holds back and tensions components which are wrapped around it.
